RANSOME BROWN, OF WEST EDMESTON, NEW YORK.

Letters Patent No. 63,007, dated March 19, 1867.

IMPROVEMENT IN WATER ELEVATORS.

The Schedule referred to in these Letters Patent and making part of the same.

TO ALL WHOM IT MAY CONCERN:

Be it known that I, RANSOME BROWN, of West Elmeston, in the county of Otsego, and in the State of New York, have invented certain new and useful Improvements in "Water Elevators;" and do hereby declare that the following is a full, clear, and exact description thereof, reference being had to the accompanying drawings and to the letters of reference marked thereon. In the annexed drawings, making a part of this specification—

A represents the frame of the well, which is provided with suitable bearings at its top for supporting the windlass B. D represents the ropes which connect the bucket C to the windlass. The bucket is provided with an opening in its bottom over which is placed a valve, so that it may fill itself and be closed by said valve when being drawn upward. As the bucket nears the spout b, there is a curved hook, a, inside the well-frame for tilting the bucket and causing the contents to drop into the spout. e represents an eccentric, which I prefer to term a "combined stop and brake," and which is horizontally attached to the side of the top portion of the well-frame, as shown in Figure 1 of the annexed drawings. This combined stop and brake is cast of metal or made of wood, and composed of a handle and curved end. This is secured to the frame by means of a metal bar, (bent to suit,) d, so as to allow the curved end to rest directly beneath the end of the windlass and to be readily worked upon its pivot z. The curved end y is constructed heavier than the handle, and ordinarily falls so that the curve will not be against the under side of the windlass; but the point x is intended to act as a cam, and will cause the suspension of the bucket in any position by its own operation, so that it is only necessary for the operator to force down the end of the handle and relieve the friction to allow the weight of the bucket to force itself into the well. When it is desired to use the eccentric as a brake, it will readily be seen that it is only necessary to force the handle down far enough to cause the curve to press against the windlass.

I am aware that the stop e has been used heretofore for the purpose of checking the windlass, I therefore make no claim to this device.

I claim the arrangement of the windlass B, stop C, pivoted to the bar d, bucket C, with its valve and curved hook a, all constructed and operating as set forth.

In testimony that I claim the foregoing, I have hereunto set my hand and seal this 21st day of November, 1866.

RANSOME BROWN.
